DESIGN FOR AN ELECTRIC FAN

Walter A. Spear, Cincinnati, Ohio, assignor to
Victor Electric Products, Inc., Cincinnati, Ohio,
a corporation of Ohio

Application October 21, 1941, Serial No. 103,837

Term of patent 7 years

To all whom it may concern:

Be it known, that I, Walter A. Spear, a citizen of the United States, residing at Cincinnati, in the county of Hamilton and State of Ohio, have invented a new, original, and ornamental Design for an Electric Fan, of which the following is a specification, reference being had to the accompanying drawing, forming a part thereof.

Figure 1 is a front elevational view of an electric fan showing my new design.

Figure 2 is a side elevational view of the fan disclosed in Figure 1.

Figure 3 is a rear elevational view of the fan.

Figure 4 is a sectional view taken substantially on the line 4—4 of Figure 2, so as to show a top plan view of the base of the fan disclosed in Figure 2.

The characteristic features of my design reside in the portions shown in full lines.

I claim:

The ornamental design for an electric fan, as shown and described.

WALTER A. SPEAR.
